UNITED STATES PATENT OFFICE.

OBADIAH SEELY, OF SYRACUSE, NEW YORK, ASSIGNOR TO E. C. STEARNS & CO., OF SAME PLACE.

DOOR-HANGER.

SPECIFICATION forming part of Letters Patent No. 310,229, dated January 6, 1885.

Application filed August 2, 1884. (Model.)

To all whom it may concern:

Be it known that I, OBADIAH SEELY, of the city of Syracuse, in the county of Onondaga and State of New York, have invented new and useful Improvements in Door-Hangers, of which the following is a specification.

This invention relates to an improvement in that class of door-hangers which are employed for supporting sliding doors from the top, and which consist of an adjustable bearing or rider-bar attached to the upper edge of the door, and rollers or wheels which support the rider-bar and run on horizontal rails above the door.

15 The object of my invention is to so construct the hanger that it can be easily adjusted and the rider-bar retained in a parallel position with the rails or upper edge of the door.

20 My invention consists, to this end, in the particular construction of the hanger, which will be hereinafter fully described, and pointed out in the claims.

In the accompanying drawings, Figure 1 represents a side elevation of one of my improved door-hangers. Fig. 2 is an end elevation thereof. Fig. 3 is a sectional top plan view, with the rider-bar and rollers removed. Figs. 4 and 5 are vertical cross-sections in lines 30 *x* and *y y*, Fig. 1.

Like letters of reference refer to like parts in the several figures.

A represents the upper portion of a sliding door, and B B the horizontal rails arranged 35 above the door in the usual manner.

C C represent the wheels or rollers of the hanger, which are secured to a shaft, *c*, at the proper distance apart to run upon the rails B B.

40 D represents the base-plate of the hanger, which is secured to the upper edge of the door A in any suitable manner. The plate D is preferably provided along its lower edge with inclined ledges *d*, which fit between ears or 45 lugs *e*, having inclined inner sides, and formed on a horizontal plate, E, which is secured to the upper edge of the door by screws *f*. The plate D is attached to the horizontal plate E by sliding its lower edge between the lugs *e*, 50 and when adjusted to the proper position it is firmly secured to the plate E by a horizon-

tal screw, *g*, which is inserted in a threaded opening formed at the outer end of the plate E.

H represents the rider-bar, which rests on the axle *c* between the rollers C C, and holds 55 the latter on the track-rails B B. The rider-bar H is composed of a horizontal portion, *h*, which rests on the shaft *c*, and two downwardly-projecting arms, *h' h'*, formed on opposite ends of the horizontal portion *h*.

I represents a horizontal arm or lever, which is pivoted near its center to the base-plate D by a pivot-bolt, *i*. The lever I is preferably bifurcated, so as to straddle the raised portion *d'* of the base-plate D, to which it is pivoted, and the bifurcated arms *i'* of the lever are pivoted at their ends to the end of the arm *h'* of the rider-bar. The opposite end of the lever I is provided with a U-shaped lug, *j*, in which is arranged a screw-nut, *k*.

70 *l* represents an inclined ear or lug which is arranged at the front end of the plate D, and M represents a screw-bolt which extends from the lug *l* through the screw-nut *k* to the short arm *h'* of the rider-bar, and is connected thereto by means of a threaded socket, *n*, formed at the end of the arm *h'*. The bolt M is provided with left and right hand screw-threads *m m'*, which engage, respectively, with the screw-nut *k* and threaded socket *n* of the rider-bar. The screw-bolt M is provided with a notched head, *o*, which bears against the under side of the lug *l*, and with a collar, *o'*, which bears against the upper side of the lug. The lug *l* is provided with an open longitudinal slot, through which the bolt is inserted, the bifurcated arms or jaws of the lug which straddle the bolt being confined between the head *o* and collar *o'*. By this means the screw-bolt is prevented from moving longitudinally in 85 the lug *l*, but is free to turn therein. The screw-nut *k* is confined between the jaws of the lug *j* by means of grooves or recesses *k'*, formed on opposite sides of the nut. The faces of the grooves *k'* which bear against the inner faces of the jaws of the lug *j* are flattened and prevent the nut from turning in the lug. The upper and lower edges of the grooves *k'*, which bear against the upper and lower edges of the jaws of the lug *j*, are rounded or 90 beveled off from the center of the grooves toward their opposite ends, so as to allow the

95 100

end of the lever I, on which the lug j is formed, to be raised and lowered with the nut k as the screw-bolt M is turned, without the jaws of the lug binding against the edges of the 5 grooves in the sides of the nut. It will be seen that by turning the screw-bolt M in one or the other direction the lever I is caused to swing on its pivot i. When the bolt is turned to the right, the forward end of the lever I is 10 raised by means of the screw-nut k riding upward on the threaded portion m of the bolt while the opposite end of the lever is being lowered. As the bolt is being turned in this direction the threaded portion m' of the bolt 15 engages in the threaded socket n on the arm h² of the rider-bar and forces the same downward, while the opposite arm, h', of the rider-bar, which is pivoted to the descending end of the lever I, is also forced downward at the 20 same time. By turning the bolt M in the opposite direction the forward end of the lever I is moved down by the screw-nut k, and the rider-bar is raised by the ascending end of the lever I and the threaded socket n engaging 25 with the threaded portion m' of the bolt.

The portion of the door to which the hanger is attached can be readily raised or lowered, as may be necessary to level or adjust the door, by turning the screw-bolt M, and during such 30 adjustment the rider-bar is parallel with the upper edge of the door. The plate D is provided above the lever I with a vertical spindle, p, on which is mounted a guide or anti-friction roller, P. The roller P is so arranged 35 as to run between the rails B B and retain the wheels C C upon the rails and prevent the hanger from binding between the rails.

My improved hanger can be readily attached to the door, and possesses the requisite adjustability which enables the door to be adjusted and leveled and the rider-bar adjusted to a parallel position with the rails or top edge of the door, thus avoiding any liability of the rollers binding between the rails and the rider-bar. 45

I am aware of the pending application of Warren S. Warner, filed August 13, 1884, Serial No. 140,393, and I do not claim the improvements in the supporting-plate E and 50 base-plate D claimed therein.

I claim as my invention—

1. In a door-hanger, the combination, with the base-plate D and rider-bar H, of a pivoted lever, I, whereby the base-plate and rider-bar 55 are connected, and an adjusting-screw whereby the lever I is swung on its pivot and the

rider-bar adjusted in a horizontal position, substantially as set forth.

2. In a door-hanger, the combination, with the base-plate and rider-bar, of a lever fulcrumed on the base-plate and attached to one end of the rider-bar, and a right-and-left-hand adjusting-screw connecting the opposite ends of the rider-bar and lever with the base-plate, substantially as set forth. 60

3. In a door-hanger, the combination, with a rider-bar, H, and base-plate D, of a lever, I, pivoted to the base-plate, and provided at one of its ends with a movable screw-nut, k, and a screw-bolt, M, substantially as set forth. 65

4. In a door-hanger, the combination, with a rider-bar, H, and base-plate D, of a lever, I, pivoted to said base-plate, and provided with a movable screw-nut, k, and a bolt, M, provided with right and left hand screw-threads 70 m m', and connecting the rider-bar and base-plate and engaging with the nut k, substantially as set forth. 75

5. In a door-hanger, the combination, with the plate D, provided with a slotted lug, l, and rider-bar H, having a threaded socket, n, of a lever, I, pivoted to the rider-bar and base-plate, and provided at one of its ends with a threaded nut, k, and a bolt, M, provided with right and left hand screw-threads, and engaging 80 with the nut k and threaded socket n, substantially as set forth. 85

6. In a door-hanger, the combination, with an adjustable rider-bar and supporting-rollers, of a base-plate, D, secured to the door, 90 and a friction-roller, P, attached to said base-plate independently of the rider-bar, substantially as set forth.

7. In a door-hanger, the combination, with the base-plate D, provided with a friction-roller, P, and a slotted lug, l, of a rider-bar, H, having arms h' h² and threaded socket n, a lever, I, pivoted at its center to the base-plate and at one end to the rider-bar, and provided 95 at its opposite end with a threaded nut, k, and a screw-bolt, M, secured at its lower end to the base-plate, and provided with right and left hand screw-threads m m', engaging, respectively, with the nut k of the lever I and the socket n of the rider-bar, substantially as set forth. 100

Witness my hand this 25th day of July, 1884.

OBADIAH SEELY.
